(57) **CLAIM**

The ornamental design for a necktie with pocket, as shown and described.

DESCRIPTION

FIG. 1 is a rear perspective view of the necktie with pocket, showing the new design;

FIG. 2 is a rights side perspective view thereof;

FIG. 3 is a rear view thereof;

FIG. 4 is a front view thereof;

FIG. 5 is a right side view thereof; and,

FIG. 6 is a left side view thereof.

The uniformly dashed lines shown in the drawings illustrate portions of the necktie with pocket which form no part of the claimed design.
